CLAIM

The ornamental design for a textured confectionary, as shown and described.

DESCRIPTION

FIG. 1 is a front elevation view of a first embodiment of a textured confectionary, the rear elevation view being a mirrored image thereof;

FIG. 2 is a right side elevation view thereof, the left side elevation, top plan, and bottom plan view being identical thereto;

FIG. 3 is a front, left side, top perspective view thereof;

FIG. 4 is a front elevation view of a second embodiment of a textured confectionary, the rear elevation view being a mirrored image thereof;

FIG. 5 is a left side elevation view thereof, the right side elevation view being a mirrored image thereof;

FIG. 6 is a top plan view thereof, the bottom plan view being a mirrored image thereof;

FIG. 7 is a front, left side, top perspective view thereof;

FIG. 8 is a front elevation view of a third embodiment of a textured confectionary, the rear elevation view being a mirrored image thereof;

FIG. 9 is a left side elevation view thereof, the right side elevation view being a mirrored image thereof;

FIG. 10 is a top plan view thereof, the bottom plan view being a mirrored image thereof;

FIG. 11 is a front, left side, top perspective view thereof; FIG. 12 is a front elevation view of a fourth embodiment of a textured confectionary, the rear elevation view being a mirrored image thereof;

FIG. 13 is a left side elevation view thereof, the right side elevation view being a mirrored image thereof;

FIG. 14 is a top plan view thereof, the bottom plan view being a mirrored image thereof;

FIG. 15 is a front, left side, top perspective view thereof; FIG. 16 is a front elevation view of a fifth embodiment of a textured confectionary, the rear elevation view being a mirrored image thereof;

FIG. 17 is a left side elevation view thereof, the right side elevation view being a mirrored image thereof;

FIG. 18 is a top plan view thereof, the bottom plan view being a mirrored image thereof;

FIG. 19 is a front, left side, top perspective view thereof; FIG. 20 is a front elevation view of a sixth embodiment of a textured confectionary, the rear elevation view being a mirrored image thereof;

FIG. 21 is a right side elevation view thereof, the left side elevation, top plan and bottom plan view being identical thereto;

FIG. 22 is a front, left side, top perspective view thereof; FIG. 23 is a front elevation view of a seventh embodiment of a textured confectionary, the rear elevation view being a mirrored image thereof;

FIG. 24 is a left side elevation view thereof, the right side elevation view being a mirrored image thereof;

FIG. 25 is a top plan view thereof, the bottom plan view being a mirrored image thereof;

FIG. 26 is a front, left side, top perspective view thereof; FIG. 27 is a front elevation view of an eighth embodiment of a textured confectionery, the rear elevation view being a mirrored image thereof;

FIG. 28 is a left side elevation view thereof, the right side elevation view being a mirrored image thereof;

FIG. 29 is a top plan view thereof, the bottom plan view being a mirrored image thereof;

FIG. 30 is a front, left side, top perspective view thereof; FIG. 31 is a front elevation view of a ninth embodiment of a textured confectionary, the rear elevation view being a mirrored image thereof;

FIG. 32 is a left side elevation view thereof, the right side elevation view being a mirrored image thereof;

FIG. 33 is a top plan view thereof, the bottom plan view being a mirrored image thereof;

FIG. 34 is a front, left side, top perspective view thereof; FIG. 35 is a front elevation view of a tenth embodiment of a textured confectionary, the rear elevation view being a mirrored image thereof;

FIG. 36 is a left side elevation view thereof, the right side elevation view being a mirrored image thereof;

FIG. 37 is a top plan view thereof, the bottom plan view being a mirrored image thereof; and,

FIG. 38 is a front, left side, top perspective view thereof.
